UNITED STATES PATENT OFFICE.

HERMANN LEMP, OF ERIE, PENNSYLVANIA, ASSIGNOR TO GENERAL ELECTRIC COMPANY, A CORPORATION OF NEW YORK.

CARBURETING APPARATUS FOR INTERNAL-COMBUSTION ENGINES.

1,251,390.

Specification of Letters Patent. Patented Dec. 25, 1917.

Application filed June 17, 1914. Serial No. 845,610.

To all whom it may concern:

Be it known that I, HERMANN LEMP, a citizen of the United States, residing at Erie, county of Erie, State of Pennsylvania, 5 have invented certain new and useful Improvements in Carbureting Apparatus for Internal-Combustion Engines, of which the following is a specification.

This application is a continuation in part 10 of my application Serial No. 830,153, filed April 7, 1914.

The present invention relates to carbureting apparatus for internal combustion engines of the type designed to run on an oil 15 heavier than gasoline and is particularly directed to kerosene engines.

As is well known, an engine of this type cannot be readily started on kerosene although after being started and well heated 20 it will operate satisfactorily thereon. It is, therefore, customary to start such engines on gasoline and afterward change over to kerosene by the manipulation of some sort of valve means. To this end it has heretofore been customary to provide two separate supplies of oil for such engines, one 25 gasoline and the other kerosene, and suitable means for changing over from one to the other.

According to the Fire Underwriters' rules 30 kerosene is classed as being comparatively safe and its storage on premises is not considered unfavorably, while gasoline is classed as being very dangerous and the storage 35 of even a small quantity on premises is considered as greatly increasing the risk. According to the Underwriters' rules, therefore, it is permissible to have only a very limited amount of gasoline on any premises 40 at one time, without having the premises classed as a gasoline risk.

The effect of an arrangement in connection 45 with kerosene engines as just described has been to convert what would ordinarily be classed as a safe risk, *i. e.*, kerosene risk, into one classed as extremely hazardous, *i. e.*, gasoline risk, thereby greatly increasing the rates.

The object of the present invention is to 50 provide a gasoline starting arrangement for a kerosene engine which is effective in start-

ing the engine and at the same time will so meet the views of the Underwriters with reference to having gasoline on premises, as to avoid having the premises classed as a 55 gasoline risk.

In the accompanying drawings wherein I have illustrated certain forms which my invention may take, Figure 1 is a side elevation of a kerosene engine equipped with my 60 improved gasoline starting arrangement; Fig. 2 is a somewhat diagrammatic view with parts in section illustrating more clearly the arrangement of the parts to which my improvements particularly relate; 65 Fig. 3 is an enlarged view of the receptacle and container shown to the left of Fig. 2; Fig. 4 is a section on line 4—4, Fig. 8; Fig. 5 is a detail view of the gasoline carbureter needle valve taken on line 5—5, Fig. 2; and 70 Figs. 6 and 7 are detail views showing modifications.

My invention is illustrated as being applied to a multi-cylinder engine, 3 being the base thereof and 4 the cylinders. 5 is the 75 kerosene carbureter, here shown as being of the overflow type. The carbureter is provided with a dam 6 for fixing the level of the oil therein and with the adjustable needle valve 7. Kerosene is supplied to the carbureter by the pump 8 driven from the crank shaft of the engine. The suction side of the pump is connected through pipe 9 with a suitable supply of oil (not shown) and the delivery side is connected by pipe 80 10 to the carbureter 5. The overflow from the carbureter passes back to the source of supply by pipe 11. 12 is the air intake of the carbureter and 13 is the outlet pipe which conveys the mixture of air and kero- 85 sene to the heating coil 14. This coil is arranged in a casing 15 and surrounds the exhaust pipe 16 which passes through the center of the casing. By this means the exhaust gases are utilized for the purpose of 90 heating or vaporizing the charges of kerosene. The other end of the coil 14 is connected by pipe 17 to a chamber 18. Opening into this chamber is the auxiliary air inlet 19 in which is arranged the inwardly 95 opening spring controlled valve 20. Leading from the chamber 18 is the conduit 21

which connects the chamber with the inlet 22 of a carburetor 23, the outlet of which connects by conduit 24 with the manifold 25 leading to the engine cylinders. Arranged in the conduit 24 is the mixture throttle valve 26 which may be controlled through arm 27 either by hand or by a speed governor.

The carburetor 23 is the gasoline carburetor and is provided with an adjustable needle valve 28. In connection with this needle valve suitable means are provided whereby the same can never be completely shut off. To this end I may, for example, provide the valve seat with a small groove or slot, or I may provide a suitable stop cooperating with the valve to limit its movement toward closed position. In Fig. 5 I have illustrated the latter arrangement. The stem of the valve carries a wheel 28^a having a notched rim on which rides the spring pressed catch 28^b. The wheel also carries the stop 28^c. During starting this valve is opened a predetermined amount as indicated by the notches—which may be suitably numbered—to starting position. After the engine is started the valve is then turned toward closed position until the stop 28^c comes in contact with catch 28^b. In this position the valve will still be slightly open, and it so remains during normal operation.

Gasoline is supplied to the carburetor 23 through the pipe 29 which connects at its outer end with a small receptacle 30. This receptacle is open at the top and its bottom is formed by a cup-shaped member 31 having a projecting coupling 32 formed with a threaded opening 33 to receive the end of the pipe 29 and two spaced projecting lugs 34, the space between them forming a key-way 35. The receptacle is adjustably supported as by the hollow sleeve 36 which telescopes with the standard 37 and is fastened in adjusted position by the screw bolt or bolts 38. The receptacle is adapted to receive therein through its open top a sealed container in which is a quantity of gasoline just sufficient for starting the engine. This container is somewhat after the style of the safety unit used in connection with the "student's lamp" and is preferably so shaped that it cannot be readily set down anywhere except in the proper receptacle. To this end the same comprises a casing 39 having a flanged base 40 upon which is fastened the handle 41. The top of the container is closed by a stopper 42 having a threaded flange 43 provided with an opening or series of openings 44. Projecting from the outer face of the stopper is a key member 45 which, when the container is inserted into the receptacle, enters the key-way 35. In the present instance this key and key-way are shown as having straight sides with the key carried by the stopper and the key-way

at the bottom of the receptacle, but it will be understood that the key and key-way may have any desired contour and that the arrangement if desired could be reversed. The stopper may be removed for filling the container and afterward screwed and sealed into place. It will be understood that when the stopper is screwed clear down that the openings 44 will be covered by the neck of the container. The container is of such diameter as to freely slide into the receptacle and is of such depth that when its flanged base rests on the rim of the receptacle, the stopper is spaced from the bottom thereof with its key member 45 in the key-way 35.

Assuming that the engine is standing and it is desired to start the same, the needle valve 28 is turned to starting position, and a container, which may have been stored at some point without the premises, is brought in and inserted in the receptacle 30, the key entering the key-way 35. The container is then turned to break the seal and unscrew the stopper sufficiently to uncover the openings 44, and permit gasoline to flow through the pipe 29 to the carburetor 23. This flow will continue until the level in the carburetor coincides with or is slightly above the upper edges of the openings 44 as indicated by the dot-and-dash line in Fig. 2. The flow will then cease and the level will remain constant as will be readily understood. The desired level can be obtained by adjusting the receptacle 30 on the supporting standard 37. The amount of gasoline contained in the bottom of the receptacle is enough to slightly cover the opening 44 of the stopper and thus form a liquid seal to prevent the free escape of the gasoline. When this seal is broken by reason of the suction of the engine drawing gasoline from the carburetor 23 a small amount will be discharged from the container, this action taking place until the contents are discharged. As it is necessary to admit some air to the container to replace the fuel discharged, some means must be provided for the purpose. The simplest way is to provide one or more openings 30^a of suitable size and shape in the vertical wall of the receptacle. It is best to locate them near the top to prevent leakage under abnormal conditions. The supply of kerosene is shut off at the needle valve 7.

The engine is now turned over in the usual manner and started on gasoline, and after it has been running sufficiently long to get well heated, the needle valve 7 is gradually opened to supply kerosene and the needle valve 28 is turned to running position, i. e. until stop 28^c strikes catch 28^b.

The container will be of such size as to hold just sufficient gasoline to start the engine in connection with which it is being used. When the needle valve 7 is opened,

therefore, to supply kerosene the supply of gasoline will have been substantially all used up. The engine may, however, for a time operate on both gasoline and kerosene, and 5 will gradually pass from one to the other.

It will be noted that no valve is provided in pipe 29 whereby the supply of gasoline may be cut off, and as the valve 28 is always left in a partly open position, there is no 10 way for preventing all the gasoline from being used. In other words, the gasoline supply is always connected directly to the carburetor by a free passage. This lends 15 great simplicity to the apparatus and is of advantage in that it requires no care or attention on the part of the attendant whatever, as he has merely to insert the container in place and leave it there. An empty container need not be removed until it is 20 desired to insert a full one to again start the engine. By this arrangement it is assured that all the gasoline will be used up each time the engine is started.

Referring to Fig. 6, I have here illustrated a modified arrangement. In this arrangement the bottom of the receptacle 30 slopes downwardly from the outer edge to an opening into which pipe 29 connects, the opening being arranged to one side of 30 the center. The top of the container is closed by a screw threaded stopper 46 in which is arranged a spring control valve 47, the stem of which projects beyond the end of the stopper.

35 This stopper may be removed for filling the container and afterward inserted and sealed in place as explained in connection with the arrangement shown in Figs. 1 to 3. The valve 47 when seated by the spring 40 48 serves to close the small openings 49 in the stopper and this valve will also preferably be sealed. When the receptacle is inserted in the container the projecting end of 45 the valve stem strikes the bottom of the receptacle breaking the seal and opening the valve 36.

In Fig. 7 I have illustrated a still further modification in which both the receptacle and the container are provided with valves. 50 The container in this modification may be the same as that described in connection with Fig. 6 and the same reference characters have been applied to corresponding parts. In this arrangement the receptacle 30 is 55 provided with a valve 50 which may be similar to the valve 47 as used on the container. The stem of the valve passes through an opening in the guide member or cap 51 and between this cap and the valve 60 is a spring 52 for biasing the valve to closed position. The spring 52 will preferably be stronger than the spring 48. With this arrangement, when the container is inserted into the receptacle 30 the projecting end 65 of the valve stem of valve 47 will strike

against the face of valve 50, the valve 47 being first opened and then the valve 50.

The modification shown in Fig. 7 has the advantage over the arrangements shown in Figs. 3 and 6 in that it renders it much 70 more difficult for an attendant to start the engine by pouring gasoline directly into the container 30, and in some instances this arrangement might be preferred. The arrangement shown in Figs. 3 and 6, however, 75 are simpler and the arrangement shown in Fig. 3 has the advantage that no springs are required and that the closing of the container can be made possibly more positive. This latter arrangement furthermore has 80 the advantage that it would be less likely to be accidentally unsealed as a positive turning motion of the stopper is necessary to break the seal. The idea of the invention in connection with each of the forms is how- 85 ever, to make the normal way of starting the engine,—i. e., by inserting a properly filled container—so simple and convenient as compared to any other way there will be no 90 reason or object for the attendant to resort to other means.

One of the great advantages of this invention is that the container can be filled outside or can be furnished filled and sealed, and is only brought in when it is desired to 95 start the engine. Furthermore there is no gasoline present except during the comparatively short time the engine is being started.

As has already been stated, the container 100 is so shaped that it cannot be readily set down anywhere except in the proper receptacle. This is of advantage in that it removes to a great extent the liability of an attendant carelessly placing one of the 105 containers on the floor and leaving it.

In the arrangement shown, the two carburetors are arranged in series, the gasoline carburetor being arranged in advance of the kerosene carburetor with the heating coils 110 between, and with a main air inlet and an auxiliary air inlet common to the two. When the gasoline is nearly used and the level of the supply falls below the needle valve, the mixture from the kerosene carburetor, which will now be heated, will, in passing through the gasoline carburetor, 115 rapidly vaporize the remaining gasoline therein and carry it into the engine cylinders.

120 I have illustrated a heating arrangement for the kerosene which has been found to be satisfactory in practice, but my invention is not limited thereto.

Owing to the fact that the gasoline carburetor is below the kerosene carburetor all 125 danger of gasoline entering the former is avoided. By arranging the receptacle and container as shown the gasoline in the bottom of the receptacle acts as a liquid seal 130

to prevent flooding of the gasoline carburetor, the feed from one to the other only taking place when the seal is temporarily broken, the necessary air to permit this action to take place entering between the walls of the receptacle and container.

In accordance with the provisions of the patent statutes I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. The combination in an internal combustion engine, of carbureting means, means for supplying kerosene thereto, a receptacle connected to the carbureting means by a free passage, and a container holding a limited supply of gasoline just sufficient for starting the engine once which is adapted to be inserted into the receptacle, to feed its contents to the carbureting means through said free passage whereby all said gasoline will be used up during the starting period.

2. The combination in an internal combustion engine, of a kerosene carburetor, means for supplying fuel thereto, a gasoline carburetor, a receptacle connected to the gasoline carburetor by a free passage, and a container holding a limited supply of gasoline just sufficient for starting the engine once which is adapted to be inserted into the receptacle, to feed its contents to the gasoline carburetor through said free passage whereby all said gasoline will be used up during the starting period.

3. The combination in an internal combustion engine, of a kerosene carburetor, means for supplying fuel thereto, a gasoline carburetor arranged in series relation with the kerosene carburetor, common air admission means for the carburetors, a receptacle connected to the gasoline carburetor by a free passage, and a container holding a limited supply of gasoline just sufficient for starting the engine once which is adapted to be inserted into the receptacle, to feed its contents to the gasoline carburetor through said free passage whereby all said gasoline will be used up during the starting period.

4. The combination in an internal combustion engine, of a kerosene carburetor and a gasoline carburetor connected in series as regards the flow of air, the kerosene carburetor being more remote from the engine, a heating coil in the connection between the two carburetors, means for supplying fuel to the kerosene carburetor, a receptacle connected to the gasoline carburetor by a free passage, and a container holding a limited supply of gasoline just sufficient for starting the en-

gine once which is adapted to be inserted into the receptacle, to feed its contents to the gasoline carburetor through said free passage whereby all said gasoline will be used up during the starting period.

5. In combination, an internal combustion engine, a relatively heavy fuel carbureting means therefor, a heater for the mixture formed thereby, a carbureting means for a lighter fuel connected to the heavy fuel carbureting means and the heater on one side and to the engine on the other and through which said mixture flows, a receptacle which is in free communication with the second carbureting means, and a sealed container containing only a sufficient amount of light fuel to start the engine once which, when inserted in the receptacle and its seal broken, automatically discharges its contents to the second carbureting means, all said light fuel being used during the starting period.

6. In combination, an internal combustion engine, a carburetor for relatively heavy fuel, a heater for the mixture formed thereby, a shut-off valve to control the admission of heavy fuel to the carburetor, a carburetor for a lighter fuel that is in permanent and unrestricted communication with the heater and the engine and through which the heavy fuel must pass before entering the engine, a receptacle which is in free communication with the second carburetor, and a sealed container having only a sufficient amount of light fuel to start the engine once which, when inserted in the receptacle and its seal broken feeds fuel to the second carburetor only, all said light fuel being used during the starting period.

7. In combination, an internal combustion engine, a heavy fuel carburetor, a heater for the mixture formed thereby, a light fuel carburetor below the first and through which said mixture passes to the engine, a nozzle in the light fuel carburetor, a receptacle situated below the level of the heavy fuel carburetor which is in free communication with the nozzle of the light fuel carburetor and in which a small body of fuel collects during the starting period, the level of which corresponds to the level of the nozzle, a sealed container adapted to be inserted in the receptacle and whose outlet is normally submerged in said body of fuel to form a liquid seal, and means for breaking the seal to permit the fuel to flow from the container after the container has been inserted into the receptacle.

8. The combination in an internal combustion engine, of a kerosene carburetor, means for supplying fuel thereto, a gasoline carburetor having an adjustable needle valve, means for preventing the valve from being fully shut off, a receptacle, a pipe having an unrestricted passage connecting the receptacle to the carburetor, and a container

holding a limited supply of gasoline sufficient for starting the engine which is adapted to be inserted into the receptacle.

9. The combination in an internal combustion engine, of carbureting means, means for supplying kerosene thereto, a receptacle connected to the carbureting means by a free passage, a sealed container holding a limited supply of gasoline just sufficient for starting the engine once which is adapted to be inserted into the receptacle, and co-operating members carried by the receptacle and container which engage each other when the container is inserted in the receptacle for breaking the seal.

10. The combination in an internal combustion engine, of carbureting means, means for supplying kerosene thereto, a receptacle connected to the carbureting means by a free passage, a container having a stopper sealed therein and holding a limited supply of gasoline just sufficient for starting the engine once which is adapted to be inserted into the receptacle, a key-way in the receptacle, and a key carried by the stopper, said key engaging the key-way when the container is inserted into the receptacle

whereby the seal may be broken by turning the container.

11. The combination in an internal combustion engine, of carbureting means, means for supplying kerosene thereto, a receptacle connected to the carbureting means by a free passage, a sealed container holding a limited supply of gasoline just sufficient for starting the engine once which is adapted to be inserted into the receptacle, a stopper for the container having a threaded flange provided with an opening, said opening being closed when the stopper is fully screwed in place, and co-operating parts carried by the stopper and receptacle which engage each other when the container is inserted into the receptacle whereby the container may be turned to unscrew the stopper and permit the contents of the container to flow through the opening into the receptacle.

In witness whereof, I have hereunto set my hand this fifteenth day of June, 1914.

HERMANN LEMP.
